UNITED STATES PATENT OFFICE.

LANGFORD J. BOWNE, OF HOWARD BEACH, NEW YORK, ASSIGNOR TO WESTERN ELECTRIC COMPANY, INCORPORATED, OF NEW YORK, N. Y., A CORPORATION OF NEW YORK.

TESTING SYSTEM.

Application filed March 10, 1923. Serial No. 624,105.

To all whom it may concern:

Be it known that I, LANGFORD J. BOWNE, a citizen of the United States, residing at Howard Beach, in the county of Queens, 5 State of New York, have invented certain new and useful Improvements in Testing Systems, of which the following is a full, clear, concise, and exact description.

This invention relates to testing systems 10 and more particularly to systems for testing and adjusting apparatus used in signaling over telephone line circuits.

It is sometimes desirable to employ signaling current of one character suitable for 15 transmission over the line from a distant station and to provide at the receiving station a relay or other means responsive thereto for translating such signaling current into current suitable for operating the signaling 20 apparatus thereof.

As the translating means must be responsive to incoming current of the proper character, but unresponsive to current of other character, which may be impressed on 25 the line, such, for example, as impulses caused by a calling subscriber attempting to recall the operator by working the switchhook of his telephone up and down, it is desirable to provide means for readily testing 30 such translating means under such conditions in order that any necessary adjustments may be made to insure its non-response to such improper currents but its response to currents of the proper character.

It is an object of this invention to provide 35 an improved method and means for testing translating means associated with telephone lines of the aforementioned character.

This object is attained in accordance with 40 a feature of the invention by the provision of switching means so that such signaling apparatus or translating means may be disconnected from the line circuit and subjected 45 to electrical conditions simulating those under which the translating means should not respond, suitable signaling means being provided for indicating the operation 50 of such translating means under these conditions.

In accordance with another feature of the 55 invention an automatic telephone impulse sender of the usual type is employed for generating the current impulses which simulate the current impulses to which it is

desired the translating means shall not respond.

In accordance with still another feature of the invention, electromagnetic means are provided and so arranged in association 60 with the impulse sender that a fewer number of impulses are transmitted to the translating means than the number of times the impulse sender makes and breaks its pulsing contact. Other and further features will be 65 apparent from the following description when read in connection with the accompanying drawing which shows diagrammatically one embodiment of the invention.

Referring to the drawing the apparatus 70 shown above and to the right of the dotted line and designated as A represents, what is commonly known as, a composite ringer set which may be connected between a transmission line and an exchange switchboard by 75 means of cords and plugs C and C₁ which are adapted to be inserted in jacks J and J₁ so that the conductors 1 and 2 will connect with the line and conductors 3 and 4 with the switchboard. Conductors 1 and 3 are 80 normally connected by means of conductor 7 and conductors 2 and 4 by means of conductor 8 through the normal contacts and armatures of relays 5 and 6.

Bridged across the conductors 7 and 8 85 through the retardation coils 9 and 10 are the relays 11 and 12, relay 11 being adjusted to respond to ringing current of a frequency similar to that of the current of the switchboard, which in practice may be 20 cycles 90 and relay 12 being adjusted to respond only to ringing current having a frequency similar to that of the ringing current transmitted over the transmission line, which in practice, might be 135 cycles. Accordingly, 95 ringing current sent out from the switchboard over conductors 3 and 4 will cause relay 11 to operate, but relay 12 will not operate as it is adjusted to respond to current of a different frequency and ringing current coming in over the line to conductors 1 and 2 will cause the relay 12 to operate 100 but will not affect relay 11 as it is adjusted to respond to current of a lower frequency.

The operation of relay 12 causes the release of relay 13 which in turn causes relay 6 to operate to disconnect the ringer set from the switchboard conductors and to apply 20 cycle ringing current thereto, and the operation of relay 11 causes the opera- 110

tion of relay 5 which disconnects the ringer set from the line and applies 135 cycle ringing current thereto from the source 14. The operation of relay 11 also closes a circuit for the operation of relay 15 which insures the continued energization of relay 13 during the ringing interval.

It frequently happens that inductive disturbances or false current impulses are set up in composited trunk lines which tend to affect relay 12 and cause it to chatter sufficiently to allow relay 13 to release, thus causing a false ring to be transmitted to the switchboard. It has been found that one of the principal causes of these false currents in systems of this character is the generation of impulses by the operation of the switchhook of a subscriber's set in an attempt to signal the operator at the exchange when the subscriber's set is connected through a toll switching trunk and a toll cord circuit with such a composited trunk line. It, therefore, is apparent that the relay 12 should be so adjusted that it will not respond to such false impulses but will respond to regular ringing impulses of the selected frequency.

Again referring to the drawing, the apparatus and circuits to the left and below the dotted line designated as B represents the testing system of the present invention which is adapted to be connected to the composite ringer A by means of the jacks J_2 and J_3 and the cords C and C_1 . Connected across the springs 16 and 17 of the jacks J_2 and J_3 , respectively, is a relay 18 responsive to 20 cycle ringing current which controls through its armature and alternate contact a signaling device such as a bell 19. Connected across the springs 20 and 21 of the jacks J_2 and J_3 is apparatus for generating current impulses which simulate the switchhook impulses before mentioned which comprises a transformer 23, sources of current 24 and 25, and an impulse sender 22 of well known type, which is adapted to be connected with a chain of relays 26, 27, 28 and 29 by means of plug P and jack J_4 .

The invention will be more fully understood from the following description of operation. To test the relay 12 against switchhook impulses, that is, to supply impulses simulating those generated by the subscriber's switchhook when moved up and down in an attempt to signal the operator, jacks J and J_2 are connected by means of cord C and J_1 and J_3 by means of cord C_1 . Plug P is inserted into jack J_4 and the dial (not shown) of the impulse sender 22 is rotated to the right and released in the well known manner. On the closure of the shunt contact 30 of the sender relay 32 is operated in a circuit from grounded battery 31, winding of relay 32, conductor 33, sleeve contacts of jack J_4 and plug P, shunt contact 30, and

pulsing contact 34 of sender 22, tip contacts of plug P and jack J_4 , and upper armature and normal contact of relay 26 to ground. A circuit is also prepared at this time for the operation of relay 26 from grounded battery 31, relay 32, conductor 33, sleeve contacts of jack J_4 and plug P, shunt contact 30, ring contacts of P and J_4 and winding of relay 26 to ground. Relay 26, however, does not operate at this time because it is short circuited by its upper normal contact and the pulsing contact 34.

Relay 32 in operating connects the output circuit of the simulated switching trunk with the line side of the composite ringer set A over conductors 46 and 47, jacks J_2 and J_3 and cords C and C_1 .

On the first break of the pulsing contact 34 of sender 22, relay 26 operates and transfers the circuit of the pulsing contact from the upper normal contact of relay 26 to the winding of relay 27 which circuit may be traced from pulsing contact spring 34A, tip contacts of plug P and jack J_4 , upper armature and alternate contact of relay 26, conductor 36, lower normal contact 37 of relay 29, conductor 38, upper normal contact 39 of relay 28 and winding of relay 27 to ground. Relay 27, however, does not operate at this time as the pulsing contact 34 is open. Relay 26 in operating also closed a circuit from grounded battery 24 through the upper winding of retardation coil 40, lower alternate contact 41 of relay 26, upper normal contact 42 of relay 43, winding 44 of transformer 23, upper alternate contact of relay 32, conductor 46, spring 20 of jack J_2 , tip conductor of cord C, tip spring of jack J, conductor 1, upper normal contact of relay 5, conductor 7, retardation coil 9, winding of relay 12, conductor 8, lower normal contact of relay 5, conductor 2, ring spring of jack J_1 , ring conductor of cord C_1 , spring 21 of jack J_3 , conductor 47, armature and lower alternate contact of relay 32, winding 48 of transformer 23, lower normal contact of relay 43, and lower winding of retardation coil 40 to ground. This causes a surge of current to flow in the circuit just traced and causes a current pulse in relay 12 which tends to energize the relay.

On the first make of the pulsing contact 34 after the first break, relay 27 operates in the circuit which may be traced from grounded battery 31 winding of relay 32, conductor 33, sleeve contacts of J_4 and P, shunt contact 30 of sender 22, pulsing contact 34, tip contacts of P and J_4 , upper alternate contact of relay 26, conductor 36, lower normal contact 37 of relay 29, conductor 38, upper normal contact 39 of relay 28 and winding of relay 27 to ground. Relay 27 in operating closes a circuit for relay 28 which may be traced

from grounded battery 31, winding of relay 32, conductor 33, sleeve contacts of J_4 and P, shunt contact J_1 , sender 22, ring contacts of P and J_4 , conductor 49, upper normal 5 contact of relay 29, winding of relay 28, upper alternate contact of relay 27, winding of relay 27 to ground. Relay 28, however, does not operate at this time as it is shunted by the pulsing contact 34. Relay 27 in operating closes at its lower alternate contact 10 a circuit through the windings 50 and 51 of the transformer 23, battery 25, and relay 52 which causes a surge of current to be induced in the windings 44 and 48 of the 15 transformer 23 which flows over the circuit before traced to the composite ringer and causes another energizing pulse in the windings of relay 12. Relay 52 in operating closes a circuit through relay 43 which may 20 be traced from grounded battery, winding of relay 43, conductor 53 and upper alternate contact of relay 52 to ground. Relay 43 in operating opens at its upper and lower normal contacts the circuit for battery 24, 25 before traced, thus causing a third surge of current in the winding of relay 12.

On the second break of the pulsing contact 34, relay 28 operates as the short circuit around this relay is opened by the breaking 30 of this contact but relay 27 is held operated as the energizing circuit for relay 28 is completed through the winding of relay 27. Relay 28 in operating transfers the pulsing contact circuit from the winding of relay 27 to the winding of relay 29 which circuit 35 may be traced from spring 34A of sender 22, tip contacts of P and J_4 , upper alternate contact of relay 26, conductor 36, lower normal contact 37 of relay 29, upper alternate 40 contact of relay 28, and winding of relay 29 to ground. On the next make of the pulsing contact relay 29 operates in a circuit which may be traced from grounded battery 31, winding of relay 32, conductor 33, sleeve 45 contacts of J_4 and P, shunt contact 30 of sender 22, pulsing contact 34, tip contacts of P and J_4 , upper alternate contact of relay 26, conductor 36, lower normal contact 37 of relay 29, conductor 38 upper alternate 50 contact of relay 28, winding of relay 29 to ground. Relay 29 in operating opens the circuit for the windings of relay 27 and 28 at its upper normal contact. Relay 29 in operating also closes its lower alternate contact 53, thus preventing the relay from releasing when relay 28 is deenergized. Relay 29 in closing its lower alternate contact 53 establishes a direct energizing circuit from pulsing contact 34, tip contacts of P and J_4 , upper alternate contact of relay 26, conductor 36, lower alternate contact 53 of relay 29 and winding of relay 29 to ground. Relay 27 in releasing opens the circuit previously traced through the windings 50 and 55 51 of a transformer 23, battery 25 and relay

52 which causes a surge of current to be induced in the windings 44 and 48 which in turn causes a fourth pulse through the relay 12. On the opening of the pulsing contact after the second make relay 29 releases. On the third make of the pulsing contact the chain of operations described for the first make of the pulsing contact is repeated. These four current pulses i. e., on the closure of the lower alternate contact 75 of relay 26, closure of the lower alternate contact of relay 27, the operation of relay 43 and the opening of the lower alternate contact of relay 27, are approximately equivalent to the impulses caused by the average subscriber's working of the switchhook in an attempt to signal the operator, when the subscriber's telephone is connected through a toll switching trunk and a toll 80 circuit to a composite trunk line. 85

When the dial (not shown) of sender 22 is operated to its extreme position and released, it makes and breaks the pulsing contact 34 ten times thus causing the chain of operations just described to function five 90 times and sending five sets of impulses into relay 12 which may be sufficient if the relay is not properly adjusted to cause its armature to vibrate and allow its controlled relay 13 to release thus causing the energization of relay 6 and the connecting of ringing current from the source 54 to the conductors 3 and 4 which are connected by means of cords C and C_1 to the springs 16 and 17 across which is connected the relay 100 18 which is responsive to such ringing current, thus causing the actuation of the signaling device 19 which signifies to the test operator that the relay 12 has operated and therefore the composite ringer set is in 105 need of adjustment.

When the dial returns to normal the shunt contact 30 opens and releases all relays thus restoring the equipment to normal.

It will be obvious that the general principles herein disclosed may be embodied in many other organizations quite different from those illustrated, without departing from the spirit of the invention as defined by the following claims. 110

What is claimed is:

1. A testing system comprising electro-responsive means to be tested, means for generating and transmitting electrical impulses simulating those generated by the operation 120 of the switchhook in a subscriber's telephone set when it is connected through a toll switching trunk and a toll cord circuit with a line, switching means for connecting said generating means with said electro-responsive means, and means for indicating the response of said electro-responsive means, said generating means comprising an automatic telephone impulse sender and a plurality of relays so arranged that a different 125 130

- number of impulses are transmitted to the translating device under test than the number of times the pulsing contact of the impulse sender is made and broken.
5. 2. In a testing system, in combination, a relay to be tested, a circuit having a transformer therein, a source of direct current, an impulse sender adapted to make and break a circuit a number of times when operated and released, a plurality of relays controlled by said impulse sender and adapted to connect said current source to a winding of said transformer, means for connecting said transformer to the winding of the relay to be tested and means for indicating the response of said relay.
3. In a testing system, in combination, a relay to be tested, a circuit comprising a transformer, a source of direct current, an

impulse sender adapted to make and break a circuit a number of times when operated and released, a plurality of relays controlled by said impulse sender and adapted to connect said direct current source to a winding of said transformer and also to disconnect said source from said transformer winding to set up in the output of said transformer a series of impulses fewer in number than the number of times the pulsing contact of the impulse sender is made and broken, means for connecting said transformer to the winding of said relay to be tested, and means for indicating the response of said relay.

In witness whereof I hereunto subscribe my name this 8th day of March A. D., 1923.

LANGFORD J. BOWNE.
